THOMAS WILLIS, OF MUMBLES, SWANSEA, SOUTH WALES.

DAMPER FOR BOILER AND LIKE FURNACES.

Application filed November 10, 1926, Serial No. 147,532, and in Great Britain February 10, 1926.

This invention relates to dampers for boilers and like purposes. The object of the invention is to provide a form of damper which will obviate the accumulation of 5 hydro-carbon and other explosive gases that occurs adjacent the damper at the upper part of the flue on a large number of boilers. A further object of the invention is to improve the draught, and the efficiency 10 of the damper.

According to the present invention a damper is composed of a number of parts adapted to be extended from a compartment or accommodated within the compartment, the said compartment having associated with it passages for the free conduction of gases accumulating at the upper part of the flue.

In the preferred embodiment of this invention I provide for the said compartment a rectilinear housing adapted to accommodate a pair of damper plates which can be selectively moved out of the housing so as to be disposed one above the other 25 or so that a selected one of them is held in an inoperative position, the said housing having one or more constantly open apertures to allow the draught of the boiler shaft or chimney to draw the gases from 30 the flue.

Each damper plate is shaped to slide easily into and out of the housing, and guides depend from the housing for positioning the damper plates. One of the plates is 35 adapted to close the lower part of the flue, and the other plate is adapted to be interposed between the aforementioned plate and the housing in the upper part of the flue. The plates can be selectively individually 40 moved and each plate can be held in any selected position between the limits of its movements. For instance by utilizing only the normally lower plate the draught can be "split" by using this plate mid-way between the housing and the base of the flue.

By means of this damper, it is possible to collect the usual residue of the products of combustion, such as flue dust so as to free the main flues from dust to a large 50 extent.

In order that the invention may be clearly understood and readily carried into effect, I have appended hereto two sheets of drawings somewhat diagrammatically illustrating 55 an embodiment of same, and wherein,

Fig. 1 is a view of the complete damper, which although for convenience of space is shown horizontally disposed, is normally vertically disposed.

Fig. 2 is a cross sectional view on the 60 line A—B of Fig. 1.

Fig. 3 is a sectional side elevation of the rear end of the boiler and flues, showing the damper in position.

Fig. 4. is a sectional end view on the line 65 C—D of Fig. 3, and

Fig. 5 is a sectional view in edge elevation of Fig. 1.

Referring to the drawings, 1 designates a hollow rectilinear metal casing flanged as 70 at 2 at its upper end to receive a cap 3 having a boss 4 through which a pair of rods 5 and 6 are guided. The lower end of the housing 1 is flanged as at 7, for attachment 75 to the upper flanged end of a rectangular frame 8 which frame is formed with two parallel channels 11 and 12 in each of its vertical limbs to slidably support a pair of damper plates 13 and 14. The plate 13 is 80 adapted to slide up and down the channel 11 for the full length of the frame 8 and, if necessary, into the housing 1, whereas a suitable abutment on the frame 8 provides means whereby the plate 14 can only slide 85 between the upper edge of the plate 13 (when the plate 13 is in its lower position as in Fig. 5) and the upper end of the housing 1. The device is adapted to be positioned within a flue or other passage 90 10 for smoke, gas or the like as shown in Figures 3 and 4 whereby the plates 13 and 14 may be manipulated to control the draft through said flue or passage.

The plate 13 has the rod 5 attached to its upper end, and the plate 14 has the rod 6 95 attached to its upper end. The rods 5 and 6 have connected to them respectively a pair of chains or cables 5^a and 6^a passed over pulleys 5^b and 6^b. These cables 5^a and 6^a or chains are guided over a common pulley 15 and connected respectively to weights 5^c and 6^c. By spacing the weights so that by their relative positions they represent the relative positions of the damper plates 13 and 14, the operator can readily determine the position of the plates 13 and 14. 100

When, for example, the device is used in the flue 10 between the fire box and the stack of boiler, as shown in Figures 3 and 4, it is desirable to prevent the accumula- 110

tion of explosive gases adjacent the top of the space 15 between the boiler and the stack flue 16, and to this end the housing 1 has one or more apertures 7^a which, whatever the positions of the plates 13 and 14 always allow a free passage for the gases into the flue 16. For this purpose, the vertical channels in the housing to receive the plates 13 and 14 are provided with gaps to allow the free passage of the gases around the edges of the plates 13 and 14.

By lowering the plate 13 to its lowermost position, as indicated in dotted lines in Fig. 3, and raising the plate 14 into or partially into the housing 1, flue dust can be collected above the discharge outlet 18, and removed when desired into the conduit 19.

It will be appreciated that the area and location of the flue opening obtainable by the manipulation of the plates 13 and 14

provides for a large scope of variation, and instead of having one adjustable opening, it is possible to have two adjustable openings, when it is desired to have a split draught.

A further advantage arising out of my invention is the saving in space, as the housing 1 need only be substantially half the full height of the frame 8.

What I claim is:—

A device adapted to be positioned within a flue or other passage for controlling the draft therethrough comprising a frame, a pair of damper plates mounted in said frame for sliding movement into different overlapping and relatively separated positions, and means affording passage for gas through said frame in all positions of said plates with respect thereto.

THOMAS WILLIS.
